UNITED STATES PATENT OFFICE.

HEINRICH KORRODI, OF ESSEN-ON-THE-RUHR, GERMANY, ASSIGNOR TO FRIED. KRUPP AKTIENGESELLSCHAFT, OF ESSEN-ON-THE-RUHR, GERMANY.

GUN WITH AN INDEPENDENT SIGHTING-LINE.

1,003,115.

Specification of Letters Patent. Patented Sept. 12, 1911.

Application filed April 30, 1907. Serial No. 371,073.

To all whom it may concern:

Be it known that I, HEINRICH KORRODI, a citizen of Switzerland, and a resident of Essen-on-the-Ruhr, Germany, have invented 5 certain new and useful Improvements in Guns with an Independent Sighting-Line, of which the following is a specification.

The present invention relates to a gun with an independent sighting line.

10 The invention is shown in the accompanying drawings, in which—

Figure 1 shows, by the way of example, a side view, partly in section, of one embodiment of the invention; Fig. 2 is a corresponding rear view, also partly in section; 15 Fig. 3 is a section on line 3—3, Fig. 1, looking from above; Fig. 4 is a section on line 4—4, Fig. 3, and Fig. 5 is a part of Fig. 3, the construction being somewhat different.

20 Reference will first be had to the embodiment shown in Figs. 1 to 4. The gun barrel A is mounted to slide on the track-carrier B which by means of horizontal trunnions, of which the drawing shows only one (b'), is 25 swingingly mounted in the cradle C. The cradle is connected to the carrier B by an elevating mechanism and can, by means of a lateral training mechanism, be swung relatively to the mount L about the axis of the 30 vertical trunnion c' which is journaled in the mount.

The elevating and training mechanisms, which are not shown in the drawings, may be of any suitable construction.

35 One of two horizontal trunnions, viz. b', is provided with a cylindrical projection b² the axis of which coincides with the axis of the horizontal trunnions. This projection forms the pivot for an arm D which may be 40 termed the sight-attachment carrier. The carrier D is provided with a guide d' which embraces an adjustment segment P secured to the cradle C and curved concentrically to the axis of the trunnions. The segment has 45 teeth p' which mesh with a spiral gear E (Fig. 3) having a hand wheel e' and mounted in the guide d'. The plane through which the gun-barrel swings being perpendicular to the axis of the horizontal trunnions, will

50 be thrown out of vertical position by unevenness in the surface upon which the wheels rest, and angular movement of the

gun-barrel upon the horizontal trunnions at such times will not effect corresponding changes in angle of elevation. The sight attachment casing F is swingingly mounted in a projection d² on the carrier D through the medium of a trunnion f' and a guide rail f² which is curved concentrically to the axis of the trunnion f'. The axis of the trunnion f' extends parallel to the plane in which the axis of the bore of the gun-barrel swings during the elevation. The guide-rail f² is provided with teeth f³ (Fig. 2) which mesh with a worm G journaled in the projection d² and having a hand-wheel g'. It being understood that with a flight continuing a given number of units of time, determined by the adjustment of the fuse, the bursting height will vary with the angle of elevation 70 of the gun-barrel. The carrier D is further provided with a projection d³ having a groove that is curved concentrically to the axis of the horizontal trunnions and in which is guided a slide H provided with 75 teeth h' which mesh with a worm J (Figs. 3 and 4), the worm being journaled in the projection d³ and provided with a hand-wheel i'. On that face of the projection d³ that is remotest from the gun-barrel, a scale 80 d⁴ (Fig. 1) is drawn, serves to correct the bursting height and is adapted to be read in conjunction with a mark h² on the slide H. In addition to the mark h², the slide H is provided with a second mark h³ on which 85 can be adjusted a mark r' on an index-hand R which is rigidly secured to the projection b² of the trunnion b'. The arrangement is so selected that the axis of the trunnion f' is parallel to the axis of the bore of the gun-barrel, when the mark r' of the index-hand R registers with the mark h³ and when at the same time the mark h² registers with the zero point of the scale d⁴. The correction of 90 the bursting height is therefore effected by shifting the slide H in the projection d³ of the arm D, the mark h³ of the slide being adjusted to register with the mark r' of the index-hand R when the gun-barrel is being elevated.

The circularly curved attachment bar K which carries a sight-telescope N is guided, in the customary inclined path, in the attachment casing F in such a manner that,

when the sighting-attachment is adjusted to the desired elevation, the sighting line at the same time gets a direction in which allowance is made for the lateral deviation of the projectile that is caused by the rifling. On that face of the attachment-bar, which is remotest from the gun-barrel, elevation scales h^2 h^3 h^4 are provided, each of said scales corresponding to a certain weight of the driving charge. The edge of the casing F which co-operates with these scales is designated f' . In the casing F is journaled a spiral gear M having a hand-wheel m' and meshing with teeth h' on the attachment-bar. The sighting attachment is provided with two levels T and S. The level T is arranged in such a manner that its longitudinal axis extends parallel to the axis of the horizontal trunnions, when, on the one hand, the edge f' registers with the zero points of the scales h^2 h^3 h^4 , and when, on the other hand, the attachment casing F has the adjustment relatively to the carrier D that corresponds to the horizontal position of the wheels. The other level (S) is adjustable in a known manner and serves to eliminate or measure the terrain-angle.

In order to direct the gun at a visible (direct) target by means of the improved sighting attachment the attachment-bar K is first adjusted by means of the spiral gear M h' in such a manner that the edge f' of the attachment casing registers with that division-line of the corresponding elevation-scale (h^2 or h^3 or h^4) that corresponds to the desired range. The adjustment for correcting the bursting height will not be considered at present, and it will therefore be assumed that the mark h^2 of the slide H registers with the zero point of the scale d^4 . The sighting line of the telescope is thereupon directed against the target, the elevation being effected by swinging the attachment carrier D about the axis of the trunnions by turning the hand-wheel e' , and the lateral direction being effected by swinging the cradle C about the axis of the trunnion c' through the medium of the lateral training mechanism. If the gun has inclined position of the wheels, that is to say if the level T does not register, the attachment casing F is then swung about the axis of the trunnion f' until the level T registers, this swinging movement being effected by means of the hand-wheel g' and the worm gear G f^3 . If, after this has been done, the sighting line is not any longer directed at the target the adjustment of sighting line against the target and the adjustment of the casing F are repeated until finally the sighting line is directed at the target and the level T registers. Finally, the elevating mechanism is used for imparting such an elevation to the gun-barrel A that the mark r' of the index-hand R

registers with the mark h^3 of the slide H. The gun-barrel is then directed at the target with elimination of the influence of the inclined position of the wheels and with elimination of the influence of the lateral deviation caused by the rifling. That this is so will be understood from the following considerations: If the axis of the trunnion f' be considered the axis of the bore of a gun-barrel, there is no doubt that this assumed gun-barrel is directed with elimination of the influences of the inclined position of the wheels and of the lateral deviation caused by the rifling, for, in this instance, their relations are exactly the same as in the known guns in which the attachment-casing can be swung about an axis parallel to the axis of the bore of the gun-barrel for the purpose of eliminating the influence of the inclined position of the wheels and in which the attachment bar has an inclined position which makes up for the lateral deviation of the projectile caused by the rifling. As, however, the mark h^2 registers with the zero point of the scale d^4 and the mark r' is adjusted to register with the mark h^3 , the axis of the bore of the real gun-barrel A is, according to the prior explanations, parallel to the axis of the trunnion f' , that is to say, it is parallel to the axis of the bore of the imaginary gun-barrel, and the gun-barrel A is consequently also directed with elimination of the influence of inclined position of the wheels and of the lateral deviation caused by the twist.

If it is necessary to correct the bursting height the slide H is adjusted by means of the hand-wheel i' and the worm-gear J h' until the mark h^2 registers with that division-line of the scale d^4 which corresponds to the desired bursting height, and the mark r' of the index-hand R is thereupon again brought to register with the mark h^3 through the medium of the elevating mechanism. A change corresponding to the desired correction of the bursting height has then been imparted to the gun-barrel. The influence of the inclined position of the wheel is in this case not completely eliminated because the axis of the bore of the gun-barrel is not any longer parallel to the axis of the trunnion f' . The errors caused by this fact are, however, so small that they are of no importance in comparison with the errors of spreading which take place on firing, and no attention need, therefore, be paid thereto.

Even if the possibility of eliminating the influence of the inclined position of the wheels is left out of consideration the herein-described device presents the further advantage that the person who operates the elevating mechanism of the gun need only take care that the mark r' of the index-hand R registers with the mark h^3 of the slide H.

This fact results in much less likelihood for a mistake being made than when the person must first examine the many division lines of an elevating scale and select that division line with which the mark r' must be brought to register. This advantage is in particular prominent when there are several elevating scales, as in high elevation guns, and when the gun-barrel after each firing must first be brought into loading position and then again into firing position, as is necessary on firing at great elevations.

In Fig. 5 the index-hand R, the slide H and the projection d^3 of the attachment carrier D are provided at x with surfaces on the side toward the gun-barrel, on which surfaces are arranged the above-named marks r' h^2 h^3 and the scale d^4 . The object of this arrangement is to enable the elevation of the gun-barrel to be watched by that person of the serving-crew who is positioned on the right side of the gun and operates the elevating mechanism.

Having now described the invention, what is claimed as new is:—

1. The combination with a gun-barrel, of a sighting device carrier swingable in the same direction as the elevating movement of the gun-barrel takes place and having an axis fixed thereon which can be adjusted parallel to the axis of the bore of the gun-barrel by swinging said carrier, a sighting device comprising an adjustable part carrying the sight and means for imparting to the sighting-line an inclination corresponding to the range relatively to the axis fixed on said sighting device carrier, said adjustable part carrying the sight being adapted to partake of the swinging movement of said carrier, means for elevating said sighting device carrier independently of the gun-barrel, and a member swingable about the same axis as said carrier and provided with a mark, said member being positively connected to the gun-barrel and adapted to turn in unison therewith and said sighting device carrier having a mark adapted to register with the mark of said member, when the axis of the bore of the gun-barrel and said axis fixed on the sighting device carrier are essentially parallel to each other.

2. The combination with a gun-barrel, of a sighting device carrier swingable in the same direction as the elevating movement of the gun-barrel takes place and having an axis fixed thereon which can be adjusted parallel to the axis of the bore of the gun-barrel by swinging said carrier, a sighting device comprising an adjustable part carrying the sight and means for imparting to the sighting-line an inclination corresponding to the range relatively to the axis fixed on said sighting device carrier, said adjustable part carrying the sight being adapted

to partake of the swinging movement of said carrier, means for elevating said sighting device carrier independently of the gun-barrel, and a member swingable about the same axis as said carrier and provided with a mark, said member being positively connected to the gun-barrel and adapted to turn in unison therewith and said sighting device carrier having a mark adapted to register with the mark of said member, when the axis of the bore of the gun-barrel and said axis fixed on the sighting device carrier are essentially parallel to each other, and a correcting device comprising a slide carrying one of said marks, and a means for adjusting said slide.

3. The combination with a gun-barrel, of a sighting device carrier swingable in the same direction as the elevating movement of the gun-barrel takes place and having an axis fixed thereon which can be adjusted parallel to the axis of the bore of the gun-barrel by swinging said carrier, a sighting device comprising an adjustable part carrying the sight and means for imparting to the sighting-line an inclination corresponding to the range relatively to the axis fixed on said sighting device carrier, said adjustable part carrying the sight being adapted to partake of the swinging movement of said carrier, means for elevating said sighting device carrier independently of the gun-barrel, and a member swingable about the same axis as said carrier and provided with a mark, said member being positively connected to the gun-barrel and adapted to turn in unison therewith and said sighting device carrier having a mark adapted to register with the mark of said member, when the axis of the bore of the gun-barrel and said axis fixed on the sighting device carrier are essentially parallel to each other, and a device for correcting the bursting height comprising a slide carrying one of said marks, means for adjusting said slide, a scale for indicating the adjustment of said slide and a mark appertaining to said scale, the said scale and the mark appertaining thereto and the two first-named marks being located on the sides of said sighting device carrier and said swingable member which are remotest from the gun-barrel.

4. The combination with a gun-barrel, of a sighting device carrier swingable in the same direction as the elevating movement of the gun-barrel takes place and having an axis fixed thereon which can be adjusted parallel to the axis of the bore of the gun-barrel by swinging said carrier, a sighting device comprising an adjustable part carrying the sight, a casing therefor swingingly mounted on said carrier about the axis fixed thereon and means for imparting to the sighting-line an inclination corresponding to

the range relatively to the axis of swinging movement of said casing, said adjustable part carrying the sight being adapted to partake of the swinging movement of said carrier, means for elevating said sighting device carrier independently of the gun-barrel and a member swingable about the same axis as said carrier and provided with a mark, said member being positively connected to the gun barrel and adapted to turn in unison therewith and said sighting device carrier having a mark adapted to register with the mark of said swingable member, when the axis of the bore of the gun-barrel and said axis fixed on the sighting device carrier are essentially parallel to each other.

5. The combination with a gun carriage, of a gun barrel provided with horizontal 20 trunnions, a carrier adjustable independently of the gun barrel about the axis of the horizontal trunnions, an adjustable slide mounted in said carrier and provided with a mark, a sighting device mounted on the 25 carrier and provided with a casing adjustable relatively to the carrier about a horizontal axis other than the axis of the trunnions; and an index-hand partaking of the elevation of the gun-barrel, said slide and 30 index-hand being adapted to indicate the relative angular adjustment between the gun barrel and the carrier.

6. The combination with the gun barrel, of a sighting attachment carrier adjustable 35 independently of the gun barrel about the axis of the horizontal trunnions and carrying a scale for correcting the bursting height, an index hand partaking of the elevation of the gun barrel, and an adjustable 40 device mounted on the carrier and provided with two marks, one for the scale and the other for the index hand.

7. The combination with a gun carriage, of a gun-barrel, a carrier adjustable independently of the gun-barrel about the axis of the horizontal trunnions, an adjustable slide mounted in said carrier and provided with a mark, a sighting device mounted on the carrier and provided with a casing adjustable relatively to the carrier about a horizontal axis other than the axis of the trunnions; and an index-hand partaking of the elevation of the gun-barrel and adapted 50 to register with the mark upon said slide.

55. 8. The combination with the gun-barrel; of a carrier; means for adjusting the carrier independently of the movement of the gun-barrel and about the axis of the horizontal trunnions of the gun-barrel; a sight-attachment 60 casing carried by the carrier; means for adjusting said casing about an axis other than the axis of the trunnions; an index-hand partaking of the movement of the gun-barrel; and means for correcting the burst-

ing-height, said means comprising a slide 65 in geared relation with said carrier.

9. The combination with a trunnioned gun-barrel, of a carrier arm pivotally mounted upon one of the trunnions of said gun-barrel and provided with an arcuate 70 groove concentric therewith, an arcuate rack rigidly secured to the cradle within which the gun-barrel is trunnioned, said arcuate rack being concentric with the trunnion and provided with a projection to fit said groove, 75 geared means carried by the carrier arm for engaging said rack, a sight attachment adjustable angularly about axes in planes parallel and perpendicular to the trunnions, an index-arm rigidly secured to said trunnion 80 upon which the carrier is mounted, and means adjustable relatively to both the carrier and the index-arm whereby a preliminary adjustment to correct the bursting height is obtained. 85

10. The combination with a gun-carriage, of a gun-barrel; a carrier adjustable independently of the gun-barrel about the axis of the horizontal trunnions, a sighting-device mounted on the carrier and comprising a 90 sight-attachment adjustable about the latter to correspond to the range of the target, and a casing for the sight-attachment adjustable about an axis without the horizontal plane through the axis of the trunnions, and means 95 acting independently of the sighting-device for indicating the correction of the bursting-height.

11. The combination with a gun-carriage; of a gun-barrel; a carrier adjustable independently of the gun-barrel about the axis of the horizontal trunnions; a sighting device mounted on the carrier; a casing therefor, adjustable relatively to the carrier about an axis other than the axis of said trunnions; means for controlling the elevation 100 of the sighting-device independently of the movement of the gun-barrel; and means adjustable independently of the sighting device for indicating the correction of the 110 bursting-height. 105

12. The combination with a gun carriage, of a gun barrel, a carrier adjustable independently of the gun barrel about the axis of the horizontal trunnions and carrying a 115 scale for correcting the bursting height, a sighting device mounted on the carrier and adjustable relatively to the latter to correspond to the range of the target, an index hand partaking of the elevation of the gun 120 barrel, and a device mounted adjustably on the carrier and carrying two marks, one for the scale and the other for the index hand.

13. The combination with a gun-carriage, of a gun barrel, a carrier adjustable independently of the gun-barrel about the axis of the horizontal trunnions, a sighting-device mounted upon the carrier and comprising a 125

casing adjustable about an axis above the horizontal plane of the trunnions; a sight-attachment movable through the casing by means of gearing; and means acting independently of the sighting device whereby the correction in the bursting height is obtained.

5 The foregoing specification signed at Dus-

seldorf, Germany, this 19th day of March, 1907.

HEINRICH KORRODI.

In presence of—

M. ENGELS,

ALFRED POHLMAYER.
